(57) **CLAIM**

The ornamental design for an EPR instrument, as shown and described.

DESCRIPTION

FIG. 1 is a top right front perspective view of an embodiment of an EPR instrument;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof.

FIG. 8 is a top, right, rear perspective view thereof;

FIG. 9 is a bottom, right, rear perspective view thereof; and,

FIG. 10 is a top, right, front perspective view illustrating an extended keyboard tray.

The broken lines depict portions of the EPR instrument that form no part of the claimed design.

1 Claim, 10 Drawing Sheets
